CLAIM

The ornamental design for a display and activating card, as shown.

DESCRIPTION

FIG. 1 is a perspective view illustrating the ornamental design for a display and activating card of this invention with photoluminescent fishing flies affixed thereto;

FIG. 2 is a second perspective view of the ornamental design for a display and activating card of this invention;

FIG. 3 is a front view of the ornamental design for a display and activating card shown in FIG. 2;

FIG. 4 is a rear view of the ornamental design for a display and activating card shown in FIG. 2; and

FIG. 5 is a top view of the ornamental design for a display and activating card shown in FIG. 2;

FIG. 6 is a bottom view of the ornamental design for a display and activating card shown in FIG. 2;

FIG. 7 is a view of one side of the ornamental design for a display and activating card shown in FIG. 2; and,

FIG. 8 is a view of the side of the ornamental design for a display and activating card shown in FIG. 2 opposite the side view of FIG. 7.

In the drawings, the broken lines show photoluminescent fishing flies that form no part of the claim.
